UNITED STATES PATENT OFFICE.

JOHN HERMANN, OF SAN FRANCISCO, CALIFORNIA.

SAFE

1,123,291.

Specification of Letters Patent.

Patented Jan. 5, 1915.

Application filed September 28, 1911. Serial No. 651,724.

To all whom it may concern:

Be it known that I, JOHN HERMANN, of San Francisco, California, have invented certain new and useful Improvements in Safes, whereof the following is a specification.

My invention relates to improvements in fire proof safes, vaults, etc., and the object of which is to provide means in this class of inventions for resisting or checking the exterior effect of heat against the interior thereof, thereby insuring the safety of the contents.

To carry out my invention in practice I construct an outer casing with an inwardly projecting door jamb to which I suspend an inner casing leaving a dead air chamber between them and provide both respectively with an outer and inner wall.

Between the walls of the outer casing I fill fire-proof material which may be in powder or granulated form while the walls of the inner casing contain similar material but preferably in sheet form, all of which will be fully described in detail hereinafter and the novel combinations of the co-operating parts pointed out in the claim at the end hereof.

In the accompanying two sheets of drawings which form a part of the following specification I have illustrated my invention in what I consider its best form as I am aware many modifications may be made without changing the scope thereof, and for the purpose of this application I shall refer to my invention as applied to fire-proof safes only.

In the drawings, Figure 1, represents a sectional elevation of my improved safe showing particularly the outer and inner casings and the dead air chamber therebetween. Fig. 2, is a cross section of Fig. 1 taken on dotted line *a*.*b* showing particularly the method of suspending the inner casing. Fig. 3, is an enlarged perspective view of a broken portion of the inner casing and Fig. 4, is also an enlarged sectional plan view of a corner of my invention, showing particularly the construction of the frame-work.

50 Detailed description.

Similar characters of reference denote corresponding parts throughout the several views of the drawings, in which:

55 A represents the outer casing provided with door B: and C the inner casing also

provided with door D. The door B of the outer casing is hung thereon as at E, and is provided with the usual combination lock F, handle G and the inwardly extending stepped extension H to which are secured 60 the inner casing C and the plates forming the dead air chamber L. To the outer casing of a safe is secured an inwardly projecting stepped extension forming a door jamb 65 I having the extension K which supports the member K' provided with the lug K², which forms a stop for the door D of the inner casing, and thereby providing a dead air space 70 between the inner door and the inner casing 75 C of the outer door. As shown by Fig. 4, the plates 2 and 4 are secured to the jamb I by screws or other similar securing means which extend through openings in the jamb and through the respective plates, from 75 where they extend through the clamping members L'. It is obvious that this structure provides an efficient means for holding the plates 2 and 4 in spaced relation, and a securing device for the plates, that 80 may only be operated when the door is in an open position.

The outer casing A is formed by an outer wall 1 and an inner wall 2 the space between them being filled compactly with a heat resisting material 3 which may be of the powder or granulated form, and the inner casing C is also formed by an outer wall 4 and an inner wall 5 arranged similarly to that of the outer casing A just described, 90 but the space between these walls is preferably filled with layers consisting of sheets of heat resisting material 6 which may be held in spaced relation by any suitable means such as spacing blocks, or by forming 95 grooves or slots in upper and lower layers of sheets to accommodate the ends of the sheets extending at right angles to the upper and lower sheets. The sheets of heat resisting material are of any suitable material such as for instance, asbestos, magnesia, etc., as shown in the drawings and particularly in Fig. 3. The extension K which as before stated, forms a part of the jamb I, terminates in an apertured extension, to which is secured the inner wall 5, through the medium of the screw K⁴, the threaded portion of which being positioned in the threaded opening K⁵.

It will be noted in Figs. 2 and 4 that the doors particularly door B is constructed and arranged in the same manner as the casings

A and C including the dead-air chamber L. Between the sheets of material employed in the construction of the inner casing C dead-air spaces may be formed thereby reducing 5 the conductivity of heat through the casing. Thus, with the above construction I have formed three distinct and separate heat resisting mediums, namely the outer casing A, the dead-air chamber L and the inner 10 casing C, all of which render the contents of the inner casing safe from the exterior heat upon the outer casing A.

Believing I have produced novel and useful improvements in the class to which my 15 invention appertains and having thus described the same to be understood by mechanics skilled in the art.

What I claim and desire to secure by United States Letters Patent is:—

20 A safe comprising outer walls, a door jamb supported by one of the walls, a door jamb secured to one of the outer walls, said jamb having stepped portions terminating in a relatively straight portion, shoulders adja-

cent the straight portion, a plate having 25 one of its ends abutting one of the shoulders, a clamping member engaging one side of the plate, means extending through the clamping member and straight portion for securing the plate to the jamb, spaced plates 30 secured to the stepped portions of the jamb, the spaces between the plates forming compartments for housing heat resisting material, clamping members co-operating with the stepped portions of the jamb for clamping the plates therebetween, means extending 35 through the stepped portions, and clamping members for rigidly securing the plates to the stepped portions, said means being operated only when the door is in an 40 open position.

In testimony that I claim the foregoing I have hereto set my hand this 15th day of Aug. 1911, in the presence of witnesses.

JOHN HERMANN.

Witnesses:

BLANCHE C. CHESTER,
T. D. HAUKNIS.
